(57) **CLAIM**

The ornamental design for a mid-sole cleat as shown and described.

DESCRIPTION

FIG. 1 is a perspective view of a mid-sole cleat;

FIG. 2 is a side view thereof;

FIG. 3 is a top view thereof;

FIG. 4 is a side view thereof;

FIG. 5 is a bottom view thereof;

FIG. 6 is a front view thereof; and

FIG. 7 is a back view thereof.

The dashed lines show various portions and other elements in the Figures for the purpose of illustrating portions of the Mid-Sole Cleat that form no part of the claimed design.

1 Claim, 3 Drawing Sheets

FIG. 3

FIG. 4
